UNITED STATES PATENT OFFICE.

CLARENCE E. CROWELL, OF PORTLAND, MAINE, ASSIGNOR OF ONE-HALF TO EDWIN L. LE BUTT, OF PORTLAND, MAINE.

LIFE-SAVING SKIRT.

1,262,458.

Specification of Letters Patent. Patented Apr. 9, 1918.

Application filed October 23, 1917. Serial No. 198,082.

To all whom it may concern:

Be it known that I, CLARENCE E. CROWELL, a citizen of the United States, residing at Portland, in the county of Cumberland and 5 State of Maine, have invented certain new and useful Improvements in Life-Saving Skirts; and I do hereby declare the following to be a full, clear, and exact description of the invention, such as will enable others 10 skilled in the art to which it appertains to make and use the same.

This invention relates to improvements in life saving skirts.

The object of this invention is to provide a 15 skirt capable of being worn by bathers and is of such construction as to be deflated when worn, thus giving no suggestion, when on the wearer, as to its being a life preserver.

A still further object of this invention is 20 to provide a skirt constructed of rubberized cloth or any other suitable light material which may be readily inflated and will not interfere with the swimmer while swimming and at the same time if the swimmer is 25 attacked with cramps, or the like, any danger of drowning will be obviated when the skirt is inflated.

A further object of this invention is to 30 provide a skirt which may be readily fastened about the waist of the wearer and when once in the water it may be moved up beneath the arm pits, and it is provided with a valve which is in close proximity to the mouth of the wearer whereby it may be 35 easily inflated in a quick and short time.

A still further object of this invention is to 40 provide a skirt of this character, which will be simple, practical and comparatively inexpensive in construction, and one that can be manufactured and sold at a low cost.

With these and other objects in view, the 45 invention consists in the novel combination and arrangement of parts hereinafter more fully described and set forth in the claims hereto appended.

In the drawings

Figure 1 is a view illustrating the skirt applied to a person when out of the water and deflated,

Fig. 2 is a view illustrating the position of the skirt upon the wearer when inflated and ready for use,

Fig. 3 is a top plan view of the device deflated illustrating the plaits.

Fig. 4 is a top plan view illustrating the 55 device inflated,

Fig. 5 is a sectional view taken on the line 5—5 of Fig. 4, and

Fig. 6 is a sectional view taken on the line 6—6 of Fig. 3 illustrating the fastening 60 means or the manner in which it may be fastened about the waist of the wearer.

Like numerals of reference designate corresponding parts in all the figures of the drawings.

Referring to the drawings, the numeral 5 designates a single length of rubberized cloth or other suitable material, suitable for the purpose. The cloth is first folded centrally on its longitudinal axis to provide a 70 double thickness, as illustrated in Figs. 5 and 6. The upper open longitudinal edges of the double thickness of cloth are bent back upon themselves as at 6 and stitched as at 7 to provide an air receiving compartment 75 8.

The single length of cloth 5 or other material, is provided with a plurality of uniform plaits 9 which extend throughout the entire length of the cloth. The plaits 9 are 80 formed by providing the upper open edges of the cloth with three rows of stitches 10 which holds the plaits in position and permits the device to be readily positioned about the waist of the wearer.

The ends of the cloth are stitched as at 11 and are provided with suitable fastening means 12 which may be of the snap fastener or hook and eye construction so that the ends may be fastened in overlapping relation 90 with one another and position the device about the waist of the wearer as illustrated in Fig. 1 of the drawings.

A valve 13 of the ordinary construction is secured between the double thicknesses of 95 cloth as at 14 and this valve facilitates the inflating of the device to provide a life saver when it is positioned upon the person in the manner illustrated in Fig. 2 thereby preventing the person from drowning when 100 swimming or otherwise.

It is to be understood that the rubberized cloth 5 may be of any shade to match the various kinds of bathing suits worn, and it will also be apparent that when the device 105 is applied to the person as illustrated in Fig. 1 that it will have the appearance of an ordinary over-skirt and will lead no one

to believe that it is a life preserver. It will also be apparent that it will only be necessary, when once in the water, to move the same upwardly under the arm-pits, grasp 5 the valve in the mouth and inflate the skirt and the device is ready to be used as a life preserver.

Having thus described the invention, what is claimed is:—

- 10 1. A life saving skirt constructed of a single length of material and provided with a plurality of uniform plaits extending throughout its entire length, means for fastening the ends of the skirt together to permit the same to encircle the waist of a person, and an inflating valve carried by the skirt to permit it to be inflated when in use.
- 15 2. A life saving skirt formed of a single length of material folded on its longitudinal axis to provide a double thickness stitched at its upper edge and ends to provide an air bag, means for detachably securing the ends of the material together and about the waist

of the user, said length of material provided with uniform plaits to give the device a 25 wearing effect when deflated about the waist of the wearer, and a valve secured to the material and between the thickness to facilitate the inflating of the material when used.

3. A life saving skirt formed of rubberized 30 material comprising a single length of material folded centrally on its longitudinal axis to provide a double thickness having its longitudinal edges turned inwardly and stitched and its ends stitched to provide an 35 air bag, means for inflating the air bag, said length of material provided with uniform plaits throughout its entire length and means for fastening the material about the waist and under the arm-pits of the user. 40

In testimony whereof I affix my signature in presence of two witnesses.

CLARENCE E. CROWELL.
